US0D1026684S

(12) **United States Design Patent** (10) Patent No.: **US D1,026,684 S**
(45) Date of Patent: ** May 14, 2024

(54) **SPEED SQUARE WITH EXTENSION**

(71) Applicant: **APEX BRANDS, INC.**, Apex, NC (US)

(72) Inventors: **Brendan Michael Walsh**, Holly Springs, NC (US); **Timothy T. McKenzie**, Westminster, MD (US)

(73) Assignee: **APEX BRANDS, INC.**, Apex, NC (US)

(**) Term: **15 Years**

(21) Appl. No.: **29/812,483**

(22) Filed: **Oct. 21, 2021**

Related U.S. Application Data

(63) Continuation of application No. 17/497,406, filed on Oct. 8, 2021, now Pat. No. 11,325,413, which is a continuation of application No. 17/407,544, filed on Aug. 20, 2021, now Pat. No. 11,554,604, which is a continuation of application No. 16/345,868, filed as application No. PCT/US2017/058060 on Oct. 24, 2017, now Pat. No. 11,161,366.

(57) **CLAIM**

The ornamental design for a speed square with extension, as shown and described.

DESCRIPTION

FIG. 1 is a perspective rear side view of a speed square with extension in accordance with the present invention; FIG. 2 is a perspective front side view of the speed square with extension in an alternate configuration; and, FIG. 3 is a perspective front side view of the speed square with extension in a different alternate configuration.

(Continued)

The dash-dash broken lines shown in the drawings depict portions of the speed square with extension that form no part of the claimed design.
